US0D1011236S

(12) **United States Design Patent** (10) Patent No.: **US D1,011,236 S**
(45) Date of Patent: ** Jan. 16, 2024

(54) **MOTOR VEHICLE BODY, TOY VEHICLE BODY REPLICA, AND/OR OTHER REPLICA**

(71) Applicant: **GM GLOBAL TECHNOLOGY OPERATIONS LLC**, Detroit, MI (US)

(72) Inventor: **Thamer H. Hannona**, Northridge, CA (US)

(73) Assignee: **GM Global Technology Operations LLC**, Detroit, MI (US)

(**) Term: **15 Years**

(21) Appl. No.: **29/821,496**

(22) Filed: **Dec. 30, 2021**

(51) LOC (14) Cl. **12-08**

(52) U.S. Cl.

USPC **D12/92**

(58) **Field of Classification Search**

USPC D12/86, 90-92, 164; D21/433, 434, 533,

D21/535; 296/181.1-181.5, 183.1

CPC B62D 25/00; B62D 25/06; B62D 33/00;

Primary Examiner — Melody N Brown

CLAIM

The ornamental design for a motor vehicle body, toy vehicle body replica and/or other replica, as shown and described.

DESCRIPTION

FIG. 1 is a front and left perspective view of a motor vehicle body, toy vehicle body replica and/or other replica showing my new design;

FIG. 2 is a rear and left side perspective view thereof;

FIG. 3 is a front elevation view thereof;

FIG. 4 is a left side elevation view thereof;

FIG. 5 is a right side elevation view thereof;

FIG. 6 is a rear elevation view thereof; and,

FIG. 7 is a top plan view thereof.

The broken lines in the drawings depict portions of the motor vehicle body, toy vehicle body replica and/or other replica that form no part of the claimed design.

1 Claim, 7 Drawing Sheets
